UNITED STATES PATENT OFFICE.

PHILIP N. BRAUN, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

COMBINED LAUNDRY PRESSING MACHINE AND WORK CONVEYER.

Application filed September 4, 1924. Serial No. 735,842.

This invention has for its object a combined pressing machine and work conveyer, consisting of trays movable to and from the pressing elements of the machine from the 5 front side of the machine, mechanism for actuating the movable element of the machine, mechanism for guiding and actuating the trays, and mechanism for controlling the operations of the actuating mechanisms, 10 which mechanisms are particularly simple in construction and organization and highly efficient and durable in use.

The invention consists in the novel features and in the combinations and constructions 15 hereinafter set forth and claimed.

In describing this invention, reference is had to the accompanying drawings in which like characters designate corresponding parts in all the views.

20 Figure 1 is a side elevation of a machine embodying my invention.

Figure 2 is a plan view of the trays and tracks therefor.

25 Figure 3 is a fragmentary elevation of one of the rollers of one of the trays, and the bridge carrying said roller, the contiguous part of the frame for the tray being also shown.

30 Figure 4 is an elevation of the front portion of the machine, illustrating the controlling handles for the pressing machine and the tray mechanism.

35 Figure 5 is a detail view of the clutch mechanism and contiguous parts for controlling the movable element of the pressing machine.

Figure 6 is an elevation of the clutch housing and contiguous parts for controlling the movement of the trays.

40 Figure 7 is a detail view of the portion of the operating means for the clutch controlling the movable element of the pressing machine.

Figure 8 is a detail view of a portion of 45 the means for operating the clutch which controls the trays.

45 Figures 9 and 10 respectively are a detail side elevation and edge view of the interlock between the motion transmitting means for 50 the trays and the operating means for the clutch controlling the movable element of the pressing machine.

Figure 11 is an enlarged detail view of the operating means shown in Fig. 4.

Figure 12 is a detail view of a part seen 55 in Fig. 11.

Figure 13 is a detail view of the carding used to hold the work on the trays.

Figure 14 is a detail view of one of the 60 pins used in place of the carding.

This pressing machine and work conveyer comprises generally, a pressing machine including cooperating pressing elements, one of which is movable toward and from the other, a work conveyer comprising oppositely 65 movable trays-movable from the front side of the machine to and from between the pressing elements, one tray being movable between the elements while the other is moving from out between the elements; mechanism for 70 actuating the movable element to close and open the same; mechanism for actuating the trays; operator-operated or manually operated means for controlling the operations of said mechanisms, an interlock between the 75 operating means for the movable pressing element, and the actuating mechanism for the trays to prevent the operation of the tray mechanism when the pressing elements are closed, an interlock between the actuating 80 mechanism for the trays and the operating means for the pressing machine to prevent closing of the pressing machine when the trays are being actuated, and an interlock 85 between the manually operated means to prevent simultaneous operation thereof.

The pressing machine here shown comprises a stationary lower buck 1, a press head 2 movable toward and from the buck 1, the buck 1 being mounted upon a suitable frame 90 3, and the head 2 being carried by a yoke or lever 4, pivoted at 5 between its ends to a standard 6 rising from the frame, the yoke being provided with a counter weight 7 at its rear end which tends to open the press 95 by gravity. The actuating mechanism is also connected to the rear arm of the yoke or lever 4.

8 and 9 designate the trays movable from the front side of the frame to and from between the buck 1 and head 2, these trays being movable along tracks individual to the trays, the tracks being arranged at their inner ends to support the trays on the buck 1 or at the same level and the tracks being so shaped as 100 to guide the trays past each other when one is moving into pressing position between the buck 1 and the head 2 and the other is moving 105

out of pressing position. The trays may be of any suitable size, form and construction, and as here shown each comprises a suitable marginal frame 10 or 11, and a web 13 or 14 secured to the frame as by lacing 15. The trays are provided at their corners with rollers 18, 21 to fit the tracks, the rollers 18 at the front corners of the tray 8 running along one set of the tracks and the rollers 21 at the rear corners of said tray 8 running along another set of tracks.

15^a designates one set of tracks for the tray 8 and 16 the other set, 17 designates the tracks for the tray 9. 18 designates the rollers in 15 the front corners of the tray 8, these rollers being carried by brackets 20, Fig. 3, secured to the frame, the brackets being shaped to bridge the tracks 17 and clear the rear rollers 24 on the tray 9. 21 designates the rollers at the 20 rear corners of the tray 8, these rollers being carried on suitable axles 22 extending laterally from the rear corners of the frame 10 of the tray 8. The rollers 23 and 24 at the front and rear corners of the tray 9, are carried on 25 suitable axles on the frame 11 of the tray 9, and the tracks 17 and the tray 9 are arranged within or between the tracks 15^a and 16 for the tray 8.

The rollers are shown as formed with circumferential grooves 25, and the tracks are shown as formed T-shaped in cross section and formed with flanges 26 which extend into the grooves 25 of the rollers. The tracks 15^a and 17 are arranged at their inner ends to 30 support the trays at the same level with the webbing 13 and 14 overlying the face of the buck 1. The tracks 16 and 17 are arranged with their front end portions downwardly inclined to support the trays in a slightly inclined position when they are out from between the pressing elements, and in position to receive the work or to have the finished work removed therefrom. Each of the tracks 15^a on which the rear rollers 21 of the tray 8 35 moves is elevated at its front end and provided with a lift portion 27 approaching the front end portion, and the tracks 16 on which the rollers 18 of the front corners of the tray 8 travel is provided with a lift portion at 28 between its ends and with a horizontal portion 29 between the lift 28 and the front inclined portion. The tracks 15^a, 16 are provided with depressions or seats 30 at their rear ends, and likewise the tracks 17 are provided 40 with similar seats or depressions, and the tracks 16 and 17 are provided with stops 31 at their front ends. The depressions receive the rollers of the trays when the trays are in position between the pressing elements and permit 45 the webbing of the trays to settle on the buck 1 after the trays have been carried over the buck and lift the webbing off the buck preliminary to removing the tray from the buck. The track 17 is substantially level with the 50 exception of the depressions and of its front

inclined end, and the lift portions 27 and 28 of the tracks 15^a and 16 are arranged to lift the tray 8 upwardly out of the plane of the tray 9 passing along the track 17, so that, the trays pass each other during their movement to and from the pressing elements, the rollers 24 of the tray 9 passing under the bridges 20 of the tray 8.

The mechanism for actuating the press head 2 comprises an intermittently movable shaft 32 having an eccentric or crank 33 at one end, a connecting rod 34 mounted at one end of the crank, and having its other end pivoted at 35 to a power lever 36, which actuates toggle mechanism consisting of links 37, 38. The link 37 is pivoted at one end at 39 to the rear arm of the yoke or lever 4, and the link 38 is pivoted at 40 to the frame, the link 38 being here shown as formed rigid with the power lever 36.

As the construction of this toggle and actuating mechanism per se, forms no part of this invention, further description is thought to be unnecessary.

The shaft 32 makes a half revolution during each intermittent operation. This shaft 32 is journaled in a suitable housing 41 carried by the main frame, and is actuated from a constantly running motor means through a suitable periodic clutch contained within the housing 41. The motion is here illustrated as transferred from the motor means to the clutch by a constantly rotating worm 42, meshing with the worm wheel 43, mounted on and rotatable about the shaft 32, and a clutch 44 comprising a shiftable clutch section 44, Fig. 5, mounted on the shaft 32 to rotate therewith, and shiftable axially thereof, and clutch pins 45 shiftable by the section 44 into and out of holes 46 in the web of the worm wheel 43. The pins are guided in suitable passages in a guide disk 47 arranged adjacent the web of the worm wheel 43, and keyed thereto by a dowel pin 47^a and the motion of the clutch section 44 is yieldingly transmitted to the pins through a pressure ring 48 thrusting against shoulders on the pins, and springs as the spring 49 interposed between the pressure ring and the clutch section 44. The springs 49 permit the pins to yield during shifting of the clutch section 44 in case the pins are not initially in alignment with the holes 46 of the worm gear 43. The ends of the pins 45 and also the holes 46 are tapered to effect a ready release of the pins when the clutch section 44 is shifted out. A main spring 50 is arranged to act on the clutch section 44 to shift it out when the force tending to hold it in is discontinued.

The clutch section 44 is held in its "in" position in order that the shaft may make a half revolution after the clutch is manually shifted to its "in" position by suitable means here shown as a cam ring 51 carried within the housing 41 concentrically with the

shaft 32, and having diametrically opposite notches 52. The cam coacts with diametrically opposite followers 53 on the clutch section 44. The followers 53 are normally located in the notches 52, and when the clutch section 44 is shifted "in" manually, the followers are carried out of the notches and during the initial rotation of the clutch section 44, are carried on to the high or plane faces of the ring and travel along such high or plane faces until the shaft has made a half revolution and the followers are again brought into alignment with the notches, whereupon the spring 50 of the clutch thrusts the clutch to its "out" position.

The clutch section 44 is shifted to its "in" position by operator-operated means, termed for convenience manually operated means. This manually operated means comprises a rock shaft 54 having a handle lever 55, a rock arm 56 mounted on the rock shaft 54 and coacting with the rock arm 57 on a shaft 58, the shaft 58 having a shifter arm 59 thrusting against the end of the hub of the clutch section 44. The rock arm 56 is provided with a pawl 60, Fig. 7, which coacts with a shoulder or tooth 61 on the rock arm 57 in such a way that depressing of the handle lever 55 causes the shaft 54 to rock in a counter clockwise direction, and the pawl 60 is brought into engagement with the shoulder 61 and to actuate the lever 57 in a clockwise direction. The pawl 60 when at the end of its movement passes clear of the shoulder 61, so that, the clutch cannot be held in by holding down on the handle 55, and the handle 55 must be operated each time that the clutch section 44 is thrown "in." The weight of the arm 56 and also the action of the spring 50 returns the parts of the manually operated mechanism to their starting position. During the return movement of the rock arm 56 the pawl 60 ratchets past the shoulder 61. Suitable adjusting means as set screws 62 and 63 are provided for the pawl 60 and the shoulder 61.

The actuating means for the trays 8 and 9 comprises an intermittently rotatable shaft 64, Figs. 1 and 6, journaled in a clutch housing 65 suitably supported by the frame of the machine, and motion transmitting means between the shaft 64 and the trays. The motion transmitting means between the shaft 64 and the trays 8, 9, comprise oppositely arranged crank arms 66 and 67 on said shaft 64, rock arms 68, 69 mounted respectively at their lower ends on shafts 70, 71 journaled in a suitable fixed base 72, and connected at their upper ends to the trays 8, 9 and links 73, 74 connecting the cranks 66 and 67 respectively with the rock arms 75 and 76 mounted respectively upon the shafts 70, 71.

The arms 68 and 69 are connected to the trays by pin and slot connections, the slots 77 being provided in the arms 68, 69 and the

pins being the ends of the axles of the rollers at the front corners of the trays these pins being designated 77. Suitable springs 78 connect each of the arms 68, 69 and the trays to hold the trays from jumping from the tracks. The motion is transmitted from the constantly running motor means to the shaft 64 through a periodic or half revolution clutch located within the housing 65, this clutch being of substantially the same construction as that shown in Fig. 5. It will be understood that the clutch constructions form no part of this invention and any periodic clutch may be used.

The operator-operated or manually operated means for throwing the clutch section of the clutch contained within the housing 65 comprises a rock shaft 79 similar to the rock shaft 54 and having a handle lever 80 at its front end and also having a rock arm 81 thereon, Figs. 1 and 8, which is connected by a link 82 to a rock arm 83 mounted on the shaft 84, similar to the shaft 58 of the clutch shown in Fig. 5. This shaft 84, has a shifter arm similar to the shifter arm 59 and which coacts with the end of the hub of the shiftable clutch section of the clutch contained within the housing 65.

Upon depression of the handle 80, the shaft 79 is rocked and through the rock arm 81, link 82 and lever or arm 83, the clutch section within the housing 65 is thrown in, so that the shaft 64 makes a half revolution, moving one of the trays 8 or 9 into position between the buck 1 and head 2 and the other tray from between the buck 1 and head 2 to the front end of the tracks. During one half revolution, the tray 8 is carried into pressing position and the tray 9 out of pressing position, and during the next half revolution, the tray 9 is carried into pressing position and the tray 8 out of pressing position, the tray 8 owing to the lifts 27 and 28 in the tracks 15 and 16 passing over the tray 9 traveling along the tracks 17.

The interlock between the actuating mechanism for the head 2 and the manually operated control mechanism for controlling the actuation of the trays to prevent actuation of the trays when the head 2 is closed, as here shown comprises a shield movable with a portion of the actuating mechanism for the head 2, into the path of a part associated with the manually operated means for the clutch mechanism controlling the trays 8 and 9, the shield being out of the path of said part when the head 2 is open.

As here illustrated, the shield is carried by the power arm 36 and comprises a rock arm 85, Fig. 1, carried on the lever 36 and having a portion 86 arranged to extend into the path of a rock arm 87 on the operating shaft 79, when the lever 36 is depressed.

The interlock between the actuating mechanism for the trays and the manually oper-

ated mechanism for controlling the head 2, to prevent closing of the head when the trays are in motion, comprises a shield movable with a part of the actuating means for the trays and coacting with a part movable with the manually operated mechanism for throwing the clutch section 44 when the shaft 64 is being rotated. This interlock as here shown comprises a shield or disk 88, Figs. 1, 9 and 10 mounted on the shaft 64 and rotatable therewith and having diametrically opposite notches 89, and a rock arm 90 on the operating shaft 54 for the clutch section 44. When the head 2 is open or closed and the trays are idle, one of the notches 89 is aligned with the arm 90, so that the shaft 54 can be operated by its handle 55 to throw in the clutch section 44 which controls the opening and closing of the head 2. When however, the trays are being actuated, these notches 89 are out of alignment with the arm 90, so that, in case the handle 55 is actuated to rock the shaft 54 and the arm 90, such rocking is prevented by the fact that the arm 90 engages the face of the disk 88.

The interlock for preventing simultaneous throwing of the clutches contained within the housing 41 and the housing 65, that is, to prevent simultaneous operations of the head 2 and the trays 8, 9, comprises mechanism by which the operation of one handle 55 or 80 locks the other handle from movement.

This interlocking mechanism is illustrated in Figs. 4, 11 and 12 and includes a locking bar 92 which is shiftable endwise in one direction by the operation of the handle 55 and in the other direction by the operation of the handle 80, the bar being arranged normally in neutral position and having spaced apart shoulders 93 and 94, each arranged to be actuated by a part operated by one of the handles to shift the bar from neutral and carry the other shoulder into position to lock the other handle.

As best seen in Fig. 4, the front ends of the shafts 54 and 79 are mounted in a bar 95 supported on the frame 96 which supports the front ends of the tracks for the trays 8, 9, and the locking bar 92 is shiftable along the rear side of the bar 95, it being provided with slots 96a for receiving the shafts 54 and 79, which slots permit the endwise movement of the locking bar 92, Fig. 12.

The shafts 54 and 79 have rock arms 97 and 98 thereon, which actuate cam levers 99 and 100 pivoted at 101 and 102 to the bar 95, these cams being arranged to coact with the pins 93, 94. The rock arms 97 and 98 are connected to the cam levers by pin and slot connections.

Normally the cams are arranged in neutral position relatively to the pins 93, 94 so that, either handle can be operated, both the cams occupying an elevated position similar to that occupied by the cam 100 at the left in Figs. 4,

11. In these figures, the parts are shown in their position occupied when the handle 55 is depressed. Assuming that the press head is open, the operator may actuate either the handle lever 55 to cause the press head to close, or he may actuate the lever 80 to cause the trays to shift. Upon the operating of the lever 55 to close the machine, the cam 99 is moved into the position shown in Figures 4 and 11 and hence the lift portion 103 thereof is pressed against the pin 93, thrusting the bar 92 to the left and carrying the pin 94 farther under the cam 100. This movement of the bar to the left also carries the pin 93 onto the dwell portion 104. The lever 80 cannot be now operated to actuate the cam 100 and cause the actuation of the trays, as the bar 92 is prevented from sliding movement due to the fact that the pin 93 shoulders against the dwell portion 104 of the cam 99.

Assuming that the parts are in the position shown in Fig. 1, that is, the press head 2 is open and the operator operates the hand lever 80 to shift the trays then the cam 100 associated with the lever 80 shifts the bar 92 to the right and the bar locks the lever 55 from being shifted due to the fact that the pin 94 thrusts against the dwell portion of the cam 100.

Thus the interlock consisting of the shield 86 and arm 87 prevents operation of the trays when the head 2 is closed, and the interlock consisting of the disk 88 and arm 90 prevents closing of the head 2 while the trays are in motion, and the interlock including the bar 92 prevents simultaneous operation of the head and the trays when the shield 86 and disk 88 are both in neutral position.

The motor means for actuating the shafts 32 and 64, in the illustrated embodiment of my invention, comprises separate electric motors 106 and 107 principally for the reason that it requires more power to close the press head 2 than to actuate the trays 8, 9, and the motor 106 is a one half H. P. motor and the motor 107 is $\frac{1}{4}$ H. P. motor, although if desired, as both motors 106 and 107 are constantly running, the shafts 32 and 64 may be actuated from one motor shaft through two clutches.

The trays 13, 14 are preferably provided with means for holding portions of the work on the trays, while the work is being straightened out or stretched over other portions of the trays, such means being automatic in its action and releasable when the finished work is removed from the tray.

This means comprises small pins or hooks secured to the tray and having laterally turned pointed ends, and usually small blocks of carding 108 are attached to the fabric of the trays, so that when the article or work is engaged with the pins of one or more of these blocks of carding, other portions can be stretched or smoothed out over the parts of

the tray provided with the remaining blocks of the carding. These pins provide an anchor to pull against while arranging the work.

As here shown blocks of carding 108 are attached to the web of the trays 13, 14 at spaced apart points along the rear margin and along the side margins. Thus the operator can arrange the work on the tray, and if necessary engage or anchor one end portion on the blocks of carding at one end of the tray, and smooth out or slightly stretch the work, pulling against such carding with which the work is engaged. The blocks of carding as will be understood, consists of flexible base strips 109, and small bent wires or pins 110 therein, and as the construction of carding for use for other purposes is well known, further description thereof is thought to be unnecessary.

Instead of the carding, pins bent as shown in Fig. 14, may be used. These pins have their bills 112 thereof looped back and under the stem of the pins to a position parallel with the stems and have their heads 113, carried at the end of an angularly extending portion of the stem.

In operation, as the garment or work is laid on the web of the tray 13, one of these pins is hooked down through the work and the web of the tray, with the stem 111 under the work and the head overlying the work. The work is then manipulated or is stretched in the desired direction and another pin placed, and the operation repeated until the garment is arranged and held to suit the operator.

What I claim is:

1. The combination of a pressing machine comprising coacting pressing elements, one movable toward and from the other, a work conveyer comprising oppositely movable trays movable from the front side of the machine to between the pressing elements, one tray being movable in one direction rearwardly to between the pressing elements while the other is moving forwardly in the opposite direction from between the pressing elements, guides for the trays, power means for actuating the movable element of the machine and for actuating the trays along their guides and manual means for controlling the actuation of the movable element and the trays by the power means.

2. The combination of a pressing machine comprising coacting pressing elements, one movable toward and from the other, a work conveyer comprising oppositely movable trays movable from the front side of the machine to between the pressing elements, one tray being movable in one direction rearwardly to between the pressing elements while the other is moving forwardly in the opposite direction from between the pressing elements, guides for the trays, power means for actuating the movable element of the ma-

chine and for actuating the trays along their guides, manual means for controlling the actuation of the movable element and the trays by the power means and means for preventing the actuation of the trays when the press is closed.

3. The combination of a pressing machine comprising coacting pressing elements, one movable toward and from the other, a work conveyer comprising trays movable from the front side of the machine alternately between the pressing elements of the machine, tracks for the trays respectively arranged to guide one tray past the other as one tray is moving between the pressing elements and the other is moving out from between the pressing elements, actuated power means for actuating the movable element and for actuating the trays along the tracks, manual controls for the movable element and the trays, means for preventing the actuation of the trays when the press is closed, and means for preventing closing of the press when the tray actuating means is being operated.

4. The combination of a pressing machine comprising coacting pressing elements, one movable toward and from the other, a work conveyer comprising reciprocating trays movable oppositely to each other from the front side of the machine alternately to and from the pressing elements, one being movable to the pressing element, while the other is moving from the pressing element, motor means, connections between the motor means and the movable element to actuate the same including an intermittently movable shaft and means for controlling the intermittent movement of the shaft from the motor means, connections between the motor means and the trays including an intermittently movable shaft and means for controlling the intermittent actuation of the latter shaft from the motor means, manual means for controlling the periodic actuation of each shaft, an interlock between the first connections and the manual control means for the trays, operating to prevent the operation of the manual control means for the trays when the press is closed, and an interlock between the second connections and the manual control means for the movable pressing element to prevent the operation of the actuating means for the pressing element when the trays are being actuated.

5. The combination of a pressing machine comprising coacting pressing elements, one movable toward and from the other, a work conveyer comprising reciprocating trays movable oppositely to each other from the front side of the machine alternately to and from the pressing elements, one being movable to the pressing element, while the other is moving from the pressing element, motor means, connections between the motor means and the movable element to actuate the same

including an intermittently movable shaft and means for controlling the intermittent movement of the shaft from the motor means, connections between the motor means and the 5 trays including an intermittently movable shaft and means for controlling the intermittent actuation of the latter shaft from the motor means, manual means for controlling the periodic actuation of each shaft, an interlock between the first connections and the 10 manual control means for the trays operating to prevent the operation of the manual control means for the trays when the press is closed, an interlock between the second connections and the manual control means for the 15 movable pressing element to prevent the operation of the manual control means for the pressing element when the trays are in motion, and an interlock between the manual 20 control means for the movable pressing element and the manual control means for the trays to prevent simultaneous operation of such manual means.

6. The combination of a pressing machine 25 comprising pressing elements, one movable toward and from the other, a work conveyer comprising oppositely movable trays movable from the front side of the machine to and from the pressing elements, one tray being 30 movable rearwardly from the front of the machine to between said elements while the other tray is movable forwardly to the front side of the machine from between said elements, guides for the trays, actuating means 35 for the trays comprising rocking levers pivoted at like ends and connected at their other ends to the trays and means for actuating the levers.

7. The combination of a pressing machine 40 comprising coacting pressing elements, one movable toward and from the other, a work conveyer comprising oppositely movable trays movable from the front side of the machine to the pressing elements, one tray being 45 movable in one direction, while the other is moving in the opposite direction, fixed tracks for the trays, the tracks being arranged to support the trays at substantially the same level at their inner ends and the intermediate 50 portions of the tracks for one tray extending to a higher level than the intermediate portion of the tracks for the other tray whereby the trays pass each other during their movement in opposite directions.

55 8. The combination of a pressing machine comprising coacting pressing elements, one movable toward and from the other, a work conveyer comprising oppositely movable trays movable from the front side of the machine 60 between the pressing elements, one tray moving to between the pressing elements, while the other is moving from between the pressing elements, tracks for the trays and means for actuating the trays along the 65 tracks comprising oppositely movable rock-

ing levers connected respectively to the trays and means for actuating the levers.

9. The combination of a pressing machine comprising coacting pressing elements, one movable toward and from the other, a work conveyer comprising oppositely movable trays movable to and from the pressing elements, one being movable to pressing position when the other is moving out of pressing position, and means for actuating the trays comprising an intermittently rotatable shaft, oppositely arranged crank arms thereon, connections between the crank arms and the trays, motor means for actuating the shaft and means for controlling the intermittent 75 actuation of the shaft.

10. The combination of a pressing machine comprising coacting pressing elements, one movable toward and from the other, a work conveyer comprising oppositely movable trays movable to and from the pressing elements, one being movable to pressing position when the other is moving out of pressing position, and means for actuating the trays comprising an intermittently rotatable shaft, 80 oppositely arranged crank arms thereon and connections between the crank arms and the trays, said connections comprising rocking levers connected respectively to the trays and means for connecting the cranks and said levers, motor means for actuating the shaft and means for controlling the intermittent actuation of the shaft by said motor means.

11. The combination of a pressing machine comprising coacting pressing elements, one 100 movable toward and from the other, a work conveyer comprising a tray movable to and from between the pressing elements, motor means, motion transmitting connections between the motor means and the movable 105 pressing element including a movable member and motion transmitting means between the motor means and the tray, the first mentioned connections including an intermittently actuated manual means for controlling the 110 intermittent actuation of said pressing element by the motor means, manual means for controlling the intermittent actuation of the motion transmitting connection to the tray, a shield carried by said movable member and a part movable with the manual means for the 115 tray, the shield being movable with the movable member by which it is carried into position to obstruct the actuation of said part when the pressing element is in closed position.

12. The combination of a pressing machine comprising coacting pressing elements, one movable toward and from the other, a work conveyer comprising a tray movable to and from the pressing element, motor means, connections between the motor means and the movable pressing element including an intermittently movable member, connections 125 between the motor means and the tray in- 130

cluding a second intermittently movable member, manual means for controlling the intermittent actuation of the first member from the motor means, manual means for controlling the intermittent actuation of the second member from the motor means, a shield movable with the second intermittent member, and a part movable with the manual means for the pressing element arranged to be obstructed by said shield when said second member is being actuated.

13. The combination of a pressing machine comprising coacting pressing elements, one movable toward and from the other, a work conveyer comprising a tray movable to and from the pressing element, motor means, connections between the motor means and the movable pressing element including an intermittently movable member, connections between the motor means and the tray including a second intermittently movable member, manual means for controlling the intermittent actuation of the first member from the motor means, manual means for controlling the intermittent actuation of the second member from the motor means, shields movable with said members, a part associated with the manual means controlling the operation of the tray and arranged to obstruct by the shield associated with the first member when the movable pressing element is closed a part associated with the manual means controlling the movement of the tray and arranged to be obstructed by the second shield when the tray is being actuated, and an interlock between the manual means for preventing simultaneous operation of such manual means.

14. The combination of a pressing machine comprising coacting pressing elements, one movable toward and from the other, a work conveyer comprising a tray movable to and from the pressing element, motor means, connections between the motor means and the movable pressing element including an intermittently movable member, connections between the motor means and the tray including a second intermittently movable member, manual means for controlling the intermittent actuation of the first member from the motor means, manual means for controlling the intermittent actuation of the second member from the motor means, shields movable with said members, a part associated with the manual means controlling the operation of the tray and arranged to obstruct by the shield associated with the first member when the movable pressing element is closed a part associated with the manual means controlling the movement of the tray and arranged to be obstructed by the second shield when the tray is being actuated, and an interlock between the manual means for preventing simultaneous operation of such manual means.

15. A work holding device for pressing machines, comprising a tray having spaced blocks of carding thereon.

In testimony whereof, I have hereunto signed my name, at Syracuse, in the county of Onondaga, in the State of New York, this 2nd day of September, 1924.

PHILIP N. BRAUN.
